MARINE RUNNING LIGHT CONVERSION SHIELD FOR LANTERNS

Andre Ullmo, University Heights, and Steven J. Jambor,
Cleveland, Ohio

Application October 20, 1955, Serial No. 38,488

Term of patent 3½ years

(Cl. D48—20)

FIG. 1

FIG. 2

FIG. 3

Figure 1 is a front elevational view of the marine running light conversion shield for lanterns, embodying our new design;

Figure 2 is a left end view of the same; and

Figure 3 is a top plan view thereof.

The lens openings are lined for the colors red and green.

We claim:

The ornamental design for a marine running light conversion shield for lanterns, substantially as shown and described.
